[57] CLAIM

The ornamental design for a pierced earring holder, as shown and described.

DESCRIPTION

FIG. 1 is a perspective view of a pierced earring holder showing my new design;

FIG. 2 is a front elevational view thereof, the rear being identical in appearance;

FIG. 3 is a side elevational view thereof, the opposite side being identical in appearance;

FIG. 4 is a top plan view thereof; and

FIG. 5 is a bottom plan view thereof.

Portions of FIGS. 2 and 3 are shown broken-away for convenience of illustration.

FIG. 4
